(57) **CLAIM**

We claim the ornamental design for a work area screen, as shown and described.

DESCRIPTION

FIG. 1 is a top front-right perspective view of a work area screen;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom front-right perspective view thereof.

The crosshatching lines represent a fabric texture that forms no part of the claimed design.

1 Claim, 6 Drawing Sheets(56)
